KNIFE BLADE GRINDING MACHINE

Herbert T. Nicholas, Sandusky, Ohio, assignor to
Klotz Machine Company, Sandusky, Ohio

Application August 3, 1940, Serial No. 350,401

11 Claims. (Cl. 51—122)

The invention to be hereinafter described relates to blade grinding machines and more particularly to knife blade grinding machines.

There have been several types of machines for grinding knife blades. In such machines, one known arrangement feeds a blade across the operative path of the grinding wheel and simultaneously tilts the blade in such manner that the curved portion at and near the end will be maintained in contact with the grinding surface of the wheel edge to approximately the same extent as will the straight portion of the blade. A serious difficulty in such machines is to so construct and arrange the parts that a single operation will grind the blade completely for its full length, throughout the curve as well as the straight portion, and produce a thin cutting edge completely around the curved end clear up to the back, removing all stock necessary to produce the fine cutting edge, all the way around the end.

The main objects of the present invention are to greatly reduce or eliminate the above and other drawbacks and deficiencies and produce a simple, efficient, compact and easily operated low cost machine capable of grinding one side of a knife blade completely in a single passage by or over the grinding wheel surface, producing a thin tapered cutting edge along the entire length, including the curved end clear up to the back.

In order to more clearly disclose the construction, operation and use of the invention, reference should be had to the accompanying drawings forming part of the present application. Throughout the several figures of the drawings like reference characters designate the same parts in the different views.

In the drawings:

Fig. 1 is a side elevation of the invention, omitting most of the main frame and the driving shaft;

Fig. 2 is a left hand end view of Fig. 1, partly broken away;

Fig. 3 is a longitudinal section of Fig. 2, partly broken away, showing the movable bars and actuating parts in plan; and,

Figs. 4, 5 and 6 are, respectively, top plan view, side elevation and bottom plan view of a knife blade ground according to this invention.

The grinding wheel, its driving and feeding mechanisms and the machine frame for supporting the same form no part of the present invention. Accordingly, only enough of them has been shown to disclose the relation of the invention to them. Likewise, the hydraulic and electric mechanism and devices for reciprocating and

starting and stopping the carriage for the blade block, broadly speaking, form no part of the present application. They are, therefore, not illustrated. By such limitation, the illustration of the invention itself becomes much simpler and clearer and its construction and operation correspondingly more definite. As far as the present invention is concerned, any suitable hydraulic operating mechanism may be used and any suitable electric starting and stopping and switching mechanism. There are several of each such known on the market, to choose from.

Referring to the drawings in detail, 1 indicates the frame of the machine, of usual and well known construction. In this is mounted and operated, in well known manner, a well known type of cylindrical grinding wheel 2.

Pivoted on frame 1 is the main bracket or support 3. The pivots 4 are so disposed as to fall in a vertical plane tangent to the outer surface or circumference of the grinding wheel or cylinder 2. Only the upper pivot has been shown in the drawings. A second pivot, of course, is used at the lower end of bracket 3. It is, in all respects, a duplicate of the upper pivot. So, illustration and description of one gives full information as to both. Obviously, a third or fourth such pivot could be used but, it is doubtful if there would be any advantage in using more than two and two, of course, are necessary to properly align the bracket for purposes of the invention. By having two pivots, vertically disposed, one above the other, and in a plane tangent to the grinding wheel, the movements of the bracket 3 and the parts carried thereby, may be so related to the grinding wheel as to produce the results accomplished by this invention.

Preferably, the upper part of bracket 3 is either formed as or provided with a large U-shaped channel or head 5 extending the full depth of the upper part of the bracket. Spanning the upper side of this U which, as shown in Fig. 1, faces the operative edge or face of the grinding wheel or cylinder 2, is a strong plate 6, block or support which constitutes a way for a reciprocable carriage 7. A simple, efficient and economical mounting of carriage 7 on way 6 is by a mortise-and-tenon or dove-tail 8 or the like, along the upper side. This forms a hook from which the weight of the carriage 7 hangs. Since the center of gravity of 7 is, obviously, to the right of the face of 6, carriage 7 will swing toward 6. So, to eliminate, as far as practicable, friction between the lower part 6 and the corresponding part of 7, roller or other anti-friction

bearings 8' may be interposed. This provides simple free-sliding movement between 6 and 7.

Extending longitudinally of the carriage 7 is a plate 9 of shallow U-shaped cross-sectional outline or contour. It is disposed between parallel spaced wings or flanges the lower one of which sustains or supports it. Near one end, it is pivotally connected to the carriage by pivot pins 10. Approximately the full length of plate 9 swings horizontally about pivots 10 as a center.

On the swinging plate 9 is supported the rocking bar 11 which tips or rocks about the longitudinal axis of horizontal pivot pins 12 which extend through end flanges or ears of bar 11 and seat in the end faces of plate 9. Thus 11 swings with 9 about the pivots 10 and rocks relatively to 9 about the axis of 12. It has three separate and distinct motions, all or any two of which may be performed simultaneously or several of which may occur separately—i. e., it reciprocates with the carriage, swings with bar or plate 9, and rocks relatively to plate 9.

The horizontally swinging motion is imparted by a small contact roller or wheel 13 travelling in contact with a cam bar 14. The contour or curvature of bar 14 is greatly exaggerated, in the drawings, for clearness. Roller 13 is carried on an arm 15 secured to 9 near its free end. As the carriage is moved longitudinally, in well known manner, the roller 13 following the cam surface of 14, causes 9 to swing in accordance with the pattern of the cam surface. The arm 15 may be adjusted, as to length, by being made in several sections with screw thread connections, a stop nut being used to limit the adjustment, in well known manner.

It will be understood of course, that, preliminary to the start of the grinding operation, the blade to be ground in accordance with the pattern of cam surface of 14, is suitably secured to the knife or blade block 16 carried by the bar 11. The machine is then set or adjusted in well known manner, so that the carriage is at the beginning of the stroke with the blade in engagement with the grinding wheel at the moment of the start of the stroke. Of course, that part of the blade corresponding to the start of the cam surface of 14 is the part positioned for such starting engagement. As the carriage moves across the face of the grinding wheel the cam surface of 14, through roller 13, arm 15 and bar 9, keeps the blade edge held firmly in grinding contact from beginning to end of that operation—i. e., throughout the longitudinal or lengthwise edge, or from the beginning of the cam surface of cam bar 14, which corresponds to the beginning of the cutting edge of the blade, to the bolster or handle end. In the illustration selected, the cam surface has the curvature of a simple table knife or similar blade with a shoulder at or near the handle end. That pattern or cam surface, as will be clearly understood, can not be used to produce blade edges of different shapes, types or designs than that corresponding to it. The cam surfaces are, actually, blade patterns. For every type, shape or different grind of blade a correspondingly different pattern or cam surface of bar 14 will be used. They are all readily attachable and detachable, in well known manner and any one may replace any other, as may be desired. And, of course, the individual manufacturer or cutlery maker may readily make and attach his own cam bars to produce the particular grind that he may desire. From the above it will be understood that an unlimited number of bars 14 each having a

different cam surface or pattern may be selectively used, producing correspondingly different ground edges. And the same is true of the bars 17, its cam surfaces or patterns, and the edges ground by it.

A long standing difficulty in grinding blades has been that of carrying the grinding clear around the free end or point and up to the widened back edge. The present invention uses a highly efficient and very simple means of doing this. This means comprises a device for rocking or tilting bar 11 at a predetermined time in accordance with a predetermined pattern. For this purpose, a cam bar 17 is used, having the pattern corresponding to the grind to be given the free end or point of the particular blade. An arm 19 is fixed to the upper part of rocking bar 11 at a point near the free end of swinging plate 9 and carries a roller 18 adapted to follow the pattern of cam bar 17. Bar 17 is so placed in the assembly that, as the carriage moves across the grinding wheel, roller 18 will traverse the pattern or cam on 17 and this will move 18 vertically, thereby rocking 11 around axis 12. This, of course, is so timed as to take place during engagement of the blade end, tip or point with the grinding wheel. The knife blade or other blade to be ground is secured, in well known manner, to the block or holder 16 carried by rocking bar 11 and is mounted thereon in such manner that its longitudinal axis is in the same horizontal plan as axis of 12 of the rocking bar 11. Consequently, in securing a blade in place, its longitudinal axis may be readily disposed in the same horizontal plane as those two axes. And that is the manner in which blades are mounted for grinding. With a blade so mounted, start of the reciprocation of the carriage starts to rock the blade about its longitudinal axis in accordance with the pattern of cam bar 17. This maintains grinding contact constantly between the curved edge of the point and the grinding wheel so that the stock will be reduced or ground off around the outer end from the bottom or cutting edge to the back. The grinding operation or job will be completely finished and no touching up required. Here, again, the outline or contour of the end, tip or point varies and each variation requires a different pattern or cam surface on bar 17. So, cam bars 17 are removably and readily attachable and detachable. As with cam bars 14, the individual user may make his own cam bars and attach them to the machines after they are received from the manufacturer of the machines. Or one or more bars having specified cam surfaces may be supplied separately with a machine and then attached as and when desired by the purchaser.

It will be obvious that cam grooves may be used instead of the cam surfaces, that the cam bars may be removably mounted in many well known ways, that the arms 15 and 19 may be connected to bars 9 and 11 in various other ways, that various other pivotal mountings of bars 9 and 11 may be used, and that many other variations may be resorted to within the field of the present invention.

From the above, it will be seen that the tangential relation between pivots 4 and grinding wheel 2 make it possible to maintain grinding contact while swinging the carriage and blade relatively to the grinding edge, thereby imparting various corresponding characteristically ground surfaces, such as flat ground, hollow or concave ground and round or convex ground, se-

lectively, by merely swinging on pivot 4. It will also be clear that as the carriage moves across the grinding surface in operative engagement with the blade, the cutting edge is automatically maintained in such grinding relation that, in a single lengthwise movement the lengthwise grinding operation is completed and all excess metal or stock is removed, eliminating all re-touching or other work and giving a completely finish-grinding job.

Likewise, it will be well understood that all ends, tips or points are automatically maintained in grinding relation to the wheel as the carriage and blade traverse the grinding wheel, producing a point finish-ground completely around the end and requiring no touching up or further operation. Thus, the entire blade, lengthwise cutting edge and end or point are both completely finish-ground in one simple continuous lengthwise movement of the carriage.

Furthermore, a very wide range of blades; blades of greatly varying shapes, outlines, curvatures, styles or types may be completely ground by this invention, by a single lengthwise movement of the carriage and require no further grinding or touching up.

It seems hardly necessary to state that blade grinding machines are usually made in pairs—right and left. One grinds one side of a blade and the other grinds the opposite side. One is complementary to the other. So, only one side is ground by the invention described. For grinding the other side a complementary machine is used, as usual. The description herein given applies equally to such complementary machine.

It is thought that the construction, operation and use of the invention will be clear from the preceding detailed description.

Many changes may be made in the construction, arrangement and disposition of the various parts of the invention within the scope of the appended claims, without departing from the field of the invention and it is meant to include all such within this application wherein only one preferred form has been illustrated, purely by way of demonstration and with no thought or intention to, in any degree limit the claim thereby.

Having thus described my invention, what I claim and desire to protect by Letters Patent is:

1. A knife blade grinding machine comprising an annular grinding wheel, a supporting bracket swingable about an axis approximately tangent to said grinding wheel, a carriage reciprocable in said bracket across the grinding path of said wheel and perpendicularly to said axis, a plate pivotally mounted at one end in said carriage to swing about said end perpendicularly toward and from said wheel, a bar carried by said plate and mounted to rock about its longitudinal axis perpendicularly to the axis of said swinging plate, means actuating said plate and said bar to operative positions and a blade holder carried by said bar.

2. A knife blade grinding machine comprising an annular grinding wheel, a supporting bracket swingable about an axis approximately tangent to said grinding wheel, a carriage reciprocable in said bracket across the grinding path of said wheel and perpendicularly to said axis, a plate pivotally mounted at one end in said carriage to swing about said end perpendicularly toward and from said wheel, a cam bar carried by said bracket and means carried by said swinging plate and engaging said cam bar during travel of the

aforesaid carriage and compelling movement of said plate in accordance with a predetermined pattern.

3. A knife blade grinding machine comprising an annular grinding wheel, a supporting bracket swingable about an axis approximately tangent to said grinding wheel, a carriage-way carried by said bracket, a carriage reciprocable on said way and having a mortise-and-tenon engagement

10 with the upper edge thereof and gravity engagement with the face thereof, a plate pivotally mounted at one end in said carriage to swing about said end perpendicularly toward and from said wheel, a cam bar carried by said bracket and means carried by said plate and engaging said cam bar and maintaining engagement therewith by gravity during travel of the aforesaid carriage, compelling movement of said plate in accordance with a predetermined pattern.

4. A knife blade grinding machine comprising an annular grinding wheel, a supporting bracket swingable about an axis approximately tangent to said grinding wheel, a carriage reciprocable in said bracket across the grinding path of said

20 wheel and perpendicularly to said axis, a plate pivotally mounted at one end in said carriage to swing about said end perpendicularly toward and from said wheel, a bar pivoted on said plate to rock about an axis perpendicularly to the axes of

25 swing of said bracket and plate, cam bars carried by the aforesaid bracket, and means carried, respectively, by said plate and bar and engaging said cam bars during travel of the aforesaid carriage, compelling movements of said plate and said bar in accordance with a predetermined pattern.

5. A knife blade grinding machine comprising an annular grinding wheel, a supporting bracket swingable about an axis approximately tangent to said grinding wheel, a carriage reciprocable in said bracket across the grinding path of said wheel and perpendicularly to said axis, a plate pivotally mounted at one end in said carriage to swing about said end perpendicularly toward and from said wheel, a bar pivoted on said plate to rock about an axis perpendicularly to the axes of

30 swing of said bracket and plate, cam bars carried by the aforesaid bracket, and means carried, respectively, by said plate and bar and simultaneously engaging said cam bars during travel of the aforesaid carriage, simultaneously swinging the plate toward the wheel and rocking the bar, as the carriage approaches the end of

35 its travel, in accordance with the predetermined curvature pattern of a selected knife blade end.

6. A knife blade grinding machine comprising an annular grinding wheel, a supporting bracket swingable about an axis approximately tangent to said grinding wheel, a carriage-way carried by said bracket, a carriage reciprocable on said way and suspended from the upper edge thereof and against the face thereof by a mortise-and-tenon connection along the upper edge thereof, the carriage being maintained by gravity in free sliding contact with the carriage-way face, a plate pivotally mounted at one end in said carriage to swing about said end perpendicularly toward and from said wheel, a bar pivoted on said plate to rock about an axis perpendicular to the axes of

40 swing of said bracket and plate and substantially parallel to the longitudinal axis of said plate, cam bars carried by the aforesaid bracket, and means carried, respectively, by said plate and bar and engaging said cam bars during travel of the aforesaid carriage, compelling movements of said

45 carriage, compelling movement of said plate in accordance with a predetermined pattern.

7. A knife blade grinding machine comprising an annular grinding wheel, a supporting bracket swingable about an axis approximately tangent to said grinding wheel, a carriage reciprocable in said bracket across the grinding path of said wheel and perpendicularly to said axis, a plate pivotally mounted at one end in said carriage to swing about said end perpendicularly toward and from said wheel, a bar pivoted on said plate to rock about an axis perpendicularly to the axes of

50 swing of said bracket and plate and substantially parallel to the longitudinal axis of said plate, cam bars carried by the aforesaid bracket, and means carried, respectively, by said plate and bar and engaging said cam bars during travel of the aforesaid carriage, compelling movements of said

55 carriage, compelling movement of said plate in accordance with a predetermined pattern.

plate and said bar in accordance with a predetermined pattern, said means being constantly urged to operative engagement by gravity of the carriage.

7. A knife blade grinding machine comprising a grinding wheel, a support adjacent said wheel, a vertically disposed carriage-way carried by said support, a vertically disposed carriage reciprocable across the grinding path of said wheel, parallel to and in free sliding contact with the face of said carriage-way, longitudinally free-sliding connections between said carriage and the upper edge of said way, said connections being off-set from the carriage, compelling gravitation of said carriage against said way, a plate pivotally mounted at one end in said support to swing about said end perpendicularly toward and from said wheel, a bar pivoted on said plate to rock about an axis perpendicular to the axis of swing of said plate, cam bars carried by the aforesaid support, and means carried, respectively, by said plate and bar and engaging said cam bars during travel of the aforesaid carriage, compelling movements of said plate and said bar in accordance with a predetermined pattern, gravity action of the aforesaid carriage maintaining operative contact between the aforesaid cam bars and the respective engaging means.

8. A knife blade grinding machine comprising a grinding wheel, a supporting bracket swingable about an axis approximately tangential to said grinding wheel, a carriage-way carried by said bracket, a carriage reciprocable on said way and having a mortise-and-tenon engagement with the upper edge thereof and gravity engagement with the face thereof, a bar pivotally mounted on said carriage to swing about an axis perpendicular to the axis of swing of the aforesaid bracket, a cam bar carried by said bracket and means carried by said bar and maintaining engagement with said cam bar by gravity during travel of the aforesaid carriage, compelling movement of said bar in accordance with a predetermined pattern.

9. A knife blade grinding machine comprising a grinding wheel, a supporting bracket swingable about an axis approximately tangential to said grinding wheel, a carriage-way carried by said bracket, a carriage reciprocable on said way and having a mortise-and-tenon engagement with the upper edge thereof and gravity engagement with the face thereof, a bar movably mounted on said

carriage and travelling with said carriage, and devices automatically moving said bar in accordance with a predetermined pattern as said carriage travels.

- 5 10. A knife blade grinding machine comprising an annular grinding wheel, a supporting bracket adjacent said wheel swingable about a stationary axis approximately tangent to said grinding wheel, a vertically disposed carriage-way carried by said bracket, a vertically disposed carriage reciprocable across the grinding face of said wheel, parallel to and in free-sliding contact with the face of said carriage-way, longitudinally free-sliding connections between said carriage and the upper edge of said way, said connections being offset from the carriage, compelling gravitation of said carriage against said way, a plate pivotally mounted at one end in said bracket to swing about said end perpendicularly toward and from said wheel, a cam bar carried by the aforesaid support, and means carried by said plate and engaging said cam bar during travel of the aforesaid carriage, compelling movements of said plate in accordance with a predetermined pattern, gravity action of the aforesaid carriage maintaining operative contact between the aforesaid cam bar and engaging means.

- 15 20 25 30 35 40 45 50 11. A knife blade grinding machine comprising an annular grinding wheel, a supporting bracket adjacent said wheel swingable about a stationary pivotal axis approximately tangent to said grinding wheel, a vertically disposed carriage-way carried by said bracket, a vertically disposed carriage reciprocable across the grinding face of said wheel, parallel to and in free-sliding contact with the face of said carriage-way, longitudinally free-sliding connections between said carriage and the upper edge of said way, said connections being offset from the carriage, compelling gravitation of said carriage against said way, a bar pivotally mounted in said carriage to rock about its longitudinal axis, a cam bar carried by the aforesaid bracket, and means carried by said bar and engaging said cam bar during travel of the aforesaid carriage, compelling movements of said bar in accordance with a predetermined pattern, gravity actuation of the aforesaid carriage maintaining operative contact between the aforesaid cam bar and engaging means.

HERBERT T. NICHOLAS.
